Design for a Fan

The schedule referred to in these Letters Patent and making part of the same.

To all whom it may concern:

Be it known that at Gustavus Anton
of Philadelphia County of Philadelphia State of Pennsylvania
have invented or produced a new and original design for a fan
and I do hereby declare the accompanying drawing with fol-
lowing explanation of the same, to form a full, clear and exact
description of the laid Design.

In the accompanying drawing: A represents the handle
of the fan, which is enlarged at its upper end, and to this enlarged
portion are secured the lower ends of a series of feathers B.

I claim:

The design for a fan substantially as herein
shown and described.

In testimony whereof I have signed my name to this
specification in the presence of two subscribing witnesses
